RESTRAINING DEVICE

Filed July 24, 1928

Inventor:
Ole K. Kjolseth,
Charles Tullor
His Attorney.

UNITED STATES PATENT OFFICE

OLE K. KJOLSETH, OF SCOTIA, NEW YORK, ASSIGNOR TO GENERAL ELECTRIC COMPANY,
A CORPORATION OF NEW YORK

RESTRAINING DEVICE

Application filed July 24, 1928. Serial No. 294,991.

My invention relates to restraining devices for locomotives or cars which are adapted to restrict oscillatory movement between the frame structure of adjacent units of a locomotive or between adjacent platform structures of locomotives or cars which are coupled together.

It is necessary to couple locomotives or cars in such manner that the frame or platform structures thereof can move laterally relative to each other in rounding a curve. As a result, when they are running along a straight portion of the track the unevenness in the track sets up oscillation or "nosing" of the frames or platform structures which is objectionable because it subjects the track to excessive lateral stresses, causes rapid wearing of the wheel flanges and also makes riding uncomfortable for passengers. It has been proposed heretofore to restrict this oscillation or "nosing" of the frames of locomotives or cars by spring pressed buffer plates engaging the coupling between them so as to resist lateral movement of the coupler relative to the frames. The use of buffers for this purpose has not been effective because the buffer plates soon become worn and offer little or no resistance to oscillation of the frames or platform structures and, moreover, such buffers do not exert any force tending to restore longitudinal alignment of the frames or platforms with each other. It has also been proposed to use springs for resisting this swaying or nosing, but they have ordinarily been connected so that the force exerted thereby on the frames increased in proportion to their displacement laterally with respect to each other. This arrangement tended to exaggerate any oscillation set up between the frame structures because considerable energy was stored up in the springs when the frames were moved laterally with respect to each other, which could only be dissipated by the frictional resistance of the coupling and restraining device. As this frictional resistance was comparatively small considerable oscillation between the frames was required to absorb the energy stored up in the springs.

The object of my invention is to provide

an improved restraining device which is adapted to exert a force tending to restore longitudinal alignment of the frame or platform structures of locomotives or cars that are coupled together, which is substantially constant throughout the range of lateral relative movement between the frame or platform structures when they are displaced relative to each other due to unevenness of the track or other causes, and which will not prevent the relative movement between the frame structures required when the locomotive or cars round a curve. I accomplish this by providing means connected between the frame or platform structures of locomotives or cars which permits relative lateral movement between them and exerts a substantially constant force urging the frame structures into longitudinal alignment when they are displaced therefrom, comprising a spring carried by each of the frame structures and a suitable linkage connecting the springs.

My invention will be more fully set forth in the following description referring to the accompanying drawing, and the features of novelty which characterize my invention will be pointed out with particularity in the claims annexed to and forming part of this specification.

The single figure of the drawing illustrates the frame structures of adjacent locomotives or cars, which are coupled together, having my improved restraining device applied thereto.

Referring to the drawing, two adjacent frames 10 of locomotives or cars are coupled together by a link 11 which is pivotally connected to each of the frames at 12, although it is to be understood that any other suitable coupling device may be used to couple the frames.

When the locomotives or cars are running on a straight portion of the track unevenness therein causes the frames 10 to oscillate or sway relative to each other. The swaying or "nosing" of the frames of the locomotives or cars is avoided in accordance with my invention by providing means for applying a substantially constant force throughout the range of their movement relative to each other

without preventing the degree of relative movement between them required in rounding a curve.

When the coupled locomotive units or cars round a sharp curve the relative movement between them may be considerable, and in order to provide for the necessary movement and at the same time exert a substantially constant force urging them into longitudinal alignment, I mount similar mechanisms on each of the frames which are connected together by a suitable linkage. In the particular construction which I have shown, as illustrative of one manner of carrying out my invention, each of these mechanisms comprises a rocker 13 having bearing portions 14 which are spaced apart transversely of the frame on which the rocker is mounted and which engage seats 15 formed in a bearing member 16 bolted at 17 to the frames. The bearing portions 14 of the rocker 13 are normally retained in engagement with seats 15 of the bearing member by coil springs 18 and 19. These springs are retained in compression between the bearing member 16 and a spring retainer 20 by a tension bar 21. The tension bar, which extends axially through the springs 18 and 19 and the spring retainer, is pivotally connected to the rocker 13 at 22 and is threaded to receive nuts 23 for adjusting the tension of the springs.

The spring retainer 20 is provided with a bearing portion 24 which slidably fits in an opening 25 formed in the frame 10 so that springs 18 and 19 will be maintained in axial alignment when they are compressed by a tilting movement of the rocker 13 on bearing member 16. The rockers 13 attached to each of the frames 10 are pivotally connected at 26 to a link 27 which is of such length that when the frames 10 are in longitudinal alignment, the bearing portions 14 of each of the rockers is retained in engagement with the seats 15 of the bearing members. It will therefore be apparent that when the frames 10 are in longitudinal alignment the springs do not exert any force thereon. However, when the frames 10 move laterally relative to each other the link 27 tilts one or both of the rockers 13 about one of the bearing portions 14 thereof in engagement with one of the seats 15 and raises the other bearing portion from the other of the seats 15 which normally engages the same so as to compress the springs 18 and 19 and exert a force tending to restore the frames to longitudinal alignment. Of course, if the relative movement between the frames is very great, as in rounding a curve, both rockers 13 will be tilted in this manner. In order to make the force substantially constant which is exerted by the springs tending to bring the frames 10 into longitudinal alignment, bearing portions 14 of the rocker 13 are so arranged rela-

tive to the pivotal connection 26 to the tension bar 22 that the lever arm of the force exerted by the springs 18 and 19 on the rocker 13, which resists tilting of the rocker, is decreased in approximately the same proportion as the compression of the spring increases. In this way the moment of force exerted by the springs on the rockers is substantially constant as this moment is equal to the product of the force of the springs and the lever arm of the force about the bearing portion, engaging the seat on the bearing member.

In view of the foregoing it is apparent that I have provided an improved restraining device between adjacent coupled locomotives or cars which will effectively resist objectionable swaying or "nosing" without preventing the relative movement between them required in rounding a curve.

What I claim as new and desire to secure by Letters Patent of the United States is:

1. In combination with two adjacent frame structures of locomotives or cars, means for connecting said frame structures together so as to permit lateral relative movement between them, and means for applying a substantially constant force urging said frame structures into longitudinal alignment when they are displaced therefrom, said means comprising a rocker and spring attached to each of said frame structures and a link connecting said rockers.

2. In combination with two adjacent frame structures of locomotives or cars, means for connecting said frame structures together so as to permit lateral relative movement between them, and means for applying a substantially constant force urging said frame structures into longitudinal alignment when they are displaced therefrom, said means comprising a rocker, a compression spring attached to each of said frame structures, and a link connecting said rockers.

3. In combination with two adjacent frame structures of locomotives or cars, means for connecting said frame structures together so as to permit lateral relative movement between them, and means for applying a substantially constant force urging said frame structures into longitudinal alignment when they are displaced therefrom, said means comprising a rocker on each of said frame structures having bearing portions spaced apart transversely of said frame structures, a spring associated with each of said rockers, means including a tension bar connected to each of said rockers between the bearing portions thereof for retaining said springs under compression, and a link connecting said rockers.

4. In combination with two adjacent frame structures of locomotives or cars, means for connecting said frame structures together so as to permit lateral relative move-

ment between them, and means for applying a substantially constant force urging said frame structures into longitudinal alignment when they are displaced therefrom, said means comprising a rocker on each of said frame structures having bearing portions spaced apart transversely of said frame structures, a spring associated with each of said rockers, a tension bar connected to each of said rockers between the bearing portions thereof for retaining said springs under compression, and a link extending transversely between said frame structures and connecting said rockers.

5 5. In combination with two adjacent frame structures of locomotives or cars, means for connecting said frame structures together so as to permit lateral relative movement between them, and means for applying a substantially constant force urging said frame structures into longitudinal alignment when they are displaced therefrom, said means comprising a rocker on each of said platforms having bearing portions spaced apart transversely of said platforms, a spring associated with each of said rockers, a tension bar connected to each of said rockers between the bearing surfaces thereon for retaining said spring under compression, a
